SETTS, A CORPORATION OF MASSACHUSETTS

MULTICOLOR-WEFT-REPLENISHING LOOM

Application filed April 6, 1928. Serial No. 268,012.

This invention relates to improvements in devices for rendering multicolor weft replenishing looms particularly adaptable for the weaving of cloths having but one color or character of filling and it is the general object of the invention to simplify constructions heretofore in use for accomplishing this general result.

In co-pending application Serial No. 263,1468 filed by Molloy and Belisle March 21, 1928 there is shown a slide member which can be applied to the ordinary multicolor weft replenishing stationary magazine in such a way as to render possible the use of filling of but one kind in all compartments of the magazine when but one shuttle is used. The device shown in said application has a pair of lifting arms one located on each side of the center of the device and the elevation of the device is effected by one or another of the vertical slides which are raised when the weft detector indicates substantial weft exhaustion to initiate replenishment. In such a construction the lifting force is always applied to one side of the attachment so that there is some cramping and consequent wearing or uncertainty of operation. It is an important object of our present invention to provide a simple attachment for a multicolor magazine which will be acted upon to be raised by direct engagement with the color slide of the magazine without necessarily depending upon the vertical slides. It is possible that in carrying out our invention part of the lifting force for our improved mechanism may be derived from one or another of the vertical slides, but the remainder of the force will preferably be derived from the color slide.

In the usual multicolor weft replenishing mechanism there is a so-called color slide, which, as generally made, employs two spaced fingers and is given both angular and longitudinal movements. The angular movements are of two kinds, one to depress the fingers every alternate beat of the loom while the shuttle is on the side of the loom opposite the magazine, while the other angular movement is effective to raise the fingers only on indicating detecting beats when an empty

shuttle is on the magazine side of the loom.

The longitudinal movements of the color slide are controlled by the pattern mechanism or box motion and said fingers are so disposed and related to the vertical slides which control the releasing of the bobbins from their respective cradles that but one vertical slide can be raised at a time. It is for this reason that the cramping due to applying a lifting force to one side of the center occurs in the attachment set forth in the aforesaid application. It is a further object of our invention to design the device forming the subject matter of our present invention so that the same will have direct engagement with the finger on the color slide which will be out of register with all the vertical slides when any slide is raised at indication of weft exhaustion.

It is found that the fingers of the aforesaid color slide when cooperating with the inner vertical slides will lie one on one side and one on the other side of the center line passing between the inner slides and we make use of this relation to prevent twisting of the attachment forming the subject matter of our present invention by actuating the latter by both fingers. It is also found that then the color slide is operatively related to either of the outside slides the finger out of register of all slides will be approximately at a mid point between the inner slides and is therefore positioned to raise the attachment without causing twisting.

The ordinary weft replenishing magazine is so constructed that a slight distance exists between the vertical slides and the supporting plate or frame of the magazine. We find that we are able to guide and position our improved attachment by forming the same with bent ends which extend behind certain of the vertical slides.

It is to be understood that our present invention is more particularly useful on an automatic box loom which has been converted into a single color loom so that there will be but one active shuttle. The box motion will be disconnected from the boxes and if desired the box motion may be disconnected from the pattern mechanism and indication for the color slide derived from the pattern mecha-

nism. It is desirable to have some part moving which is capable of giving the color slide a plurality of longitudinal positions and it is preferable that the movement of the color slide be not too frequent for a reason which will be set forth hereinafter.

With these and other objects in view which will appear as the description proceeds, our invention resides in the combination and arrangement of parts hereinafter described and set forth in the claims.

In the accompanying drawings wherein one form of our invention is shown,

Fig. 1 is a side elevation of a weft replenishing mechanism equipped with our present invention, the magazine being viewed from the center of the loom and showing one of the vertical slides in raised position,

Fig. 2 is a vertical section taken on line 20 2—2 of Fig. 1,

Figs. 3 to 8, inclusive, are diagrammatic views showing the vertical slides, color slide, and our improved attachment in different positions, as will be set forth more clearly hereinafter, and

Fig. 9 is a perspective view showing the element forming an essential part of our present invention.

Referring particularly to Figs. 1 and 2, we have shown a loom frame 20 on which is mounted a multicolor weft replenishing mechanism 21 provided with the usual transferrer arm 22. On each side of the center line of the inner plate 23 of the magazine is disposed a pair of vertical slides, said slides being indicated at 24, 25, 26 and 27, respectively. Each slide has operative connection at the lower end thereof with a stud 28 which is operatively connected to the bobbin controlling cradle not shown. In the upper part of the weft replenishing mechanism is located a rock shaft 29 operatively connected to a shuttle feeler 30.

The color slide 31 is provided with a pair of spaced fingers 32 and 33, respectively, while each of the slides 24 to 27, inclusive, is provided with an upper lug 34 and a lower lug 35 between which the fingers move horizontally. Said fingers are adapted to cooperate with the lugs in such a way that at exhaustion of weft in the active shuttle the slide corresponding to the active shuttle will be raised by cooperation between one of the fingers and the upper lug 34 corresponding to the slide to be raised. On a subsequent pick when the depleted shuttle returns the lower lug 35 of the elevated slide will be moved down by the color slide to depress the previously raised vertical slide. In this way a bobbin is advanced toward transfer position by the two step movement of the color slide. As shown more clearly in Fig. 2 the vertical slides are spaced a short distance from the frame 23 and as shown in Fig. 1 said slides may be

guided by lugs 36 fast with respect to the frame 23.

In the operation of the mechanism the color slide 31 will be moved to assume a plurality of longitudinal positions by means of a bell crank lever 37 which is operatively related to said slide by a collar 38 and which will be moved in a counter-clockwise direction by a chain 39 operatively connected to the box motion or pattern mechanism. A tension spring 40 operates to move the lever 37 and the color slide in the right hand direction as viewed in Fig. 1. By means of a depending rod 41 the fingers on the color slide may be moved downwardly on every alternate beat and upwardly on indicating detecting beats. The matter thus far described is of common construction, forming no part of our present invention other than the way in which the same cooperates with our improved attachment, and may be the same as set forth in patent to Ryon No. 1,080,748.

As previously stated, our present invention relates to improved means for raising and lowering the slides 23 to 27, inclusive, irrespective of the position of the color slide, and in carrying our invention into effect we provide a device 50 of the general form shown in Fig. 9, making the same preferably of a single piece of pressed metal. The device 50 is provided with a lower horizontally extending shelf 51 which is positioned at all times under the color slide fingers 32 and 33. Said device has an upright body portion 52 from each side of which extend lateral ears 53 which are bent back on themselves as at 54 to provide guides which extend behind the vertical slides 24 and 27 as shown in Figs. 2 and 4. Said ears prevent lateral displacement of the device 50 and also prevent the same from moving toward the center of the loom by their engagement with the specified vertical slides.

The device 50 at the upper end thereof is provided with an overhang 55 from which depends a lifting rail 56 of sufficient length to be in engaging position with the color slide fingers in all positions of the latter. Said rail 56 extends preferably forwardly of the lugs 34, although we do not wish to be limited to this construction, and said rail furthermore extends laterally on each side of the upright body portion 52. Said portion 52 lies between the inner vertical slides 25 and 26 as shown in Fig. 1 and in the diagrammatic Figs. 3, 5 and 7. The rail 56 as set forth in the particular form of the invention shown herein has no connection with the upper lugs 34 and in no way interferes with the movement of the vertical slides.

In operation, the color slide and device 50 will be in the position shown diagrammatically in Figs. 3 and 4 when the loom is operating normally with a sufficient supply of weft. As weaving continues, the weft will be

depleted and as shown herein this depletion will occur when the finger 32 is in register with vertical slide 26 with the result that the latter will be raised to the position shown in Fig. 1 and diagrammatically in Fig. 5. The raising is accompanied by an upward movement on the part of the device 50 which is brought about by engagement between the fingers 32 and 33 with the finger rail 56. By an inspection of Figs. 3 and 5 it will be seen that the raising fingers which elevate the device 50 are on opposite sides of the center of said devices so that there is very little if any tendency on the part of said devices to twist and cramp as the same is raised. Immediately following the elevation of slide 26 the color slide will move back to the position shown in Fig. 2 and the device 50 will rest on the lower lug 35 of the elevated vertical slide 26.

On the next pick of the loom the color slide will be given an angular movement in a right hand direction as viewed in Fig. 2 so that the fingers 32 and 33 will engage the shelf 51 and move the device 50 down or back to normal position. This return movement of the device 50 will cause restoration of the vertical slide 26 to its lower position by reason of the engagement between the lower lug 35 thereof and the shelf 51.

Because of the length of shelf 51 said device will always be lowered on the pick following the indication of weft exhaustion. Thus, for instance, if the color slide after raising slide 26 should move to the right to assume the dotted line position shown in Fig. 5 or the full line position shown in Fig. 7 where the finger 32 has moved out of register with slide 26, the device will nevertheless be lowered and with it any vertical slide which effected previous raising of said device.

The fingers 32 and 33 are indicated in their extreme left hand position in dotted lines in Fig. 3, from which it will be seen that the finger which is adjacent the center of the magazine will lie approximately under the center of the device 50 and will be effective to raise said device with practically no tendency to twisting.

As previously stated, it is desirable to keep the color slide in one longitudinal position for a comparatively large number of picks rather than to keep the same moving rather rapidly from one position to another. The reason for this is due to the fact that the total number of picks on a full bobbin which may be laid between replenishment and subsequent expulsion will more likely be a multiple of a small number than of a larger number. If all the bobbins wove exactly the same number of picks before calling for a transfer and that number were a multiple of the number of picks required for a complete cycle of movement on the part of the color slide, transfer would always take place from the

same vertical stack of bobbins. It is to prevent this possibility that we believe the controlling device of the color slide should move the same rather infrequently.

From the foregoing it will be seen that we have provided a very simple device of small size which is effective to bring about a transfer on the pick following that on which indication of weft exhaustion occurs independently of the position of the color slide 31. It will further be seen that the device is so constructed as to have the raising force applied thereto at two points so located that there is practically no turning movement brought to play on the device tending to twist the same. Also, it will be seen that the vertical slides which cooperate with the device are the means by which said device is held in proper position. Such a relation between the parts is more preferable than that shown in the aforementioned Molloy and Belisle application because of the fact that the location of the slides is determined very accurately by jigs etc. while the location of the slot which guides the upper portion of the device shown in the aforesaid application is not finished and remains unchanged after being cast.

Having thus described our invention it will be seen that changes and modifications may be made therein by those skilled in the art without departing from the spirit and scope of the invention and we do not wish to be limited to the details herein disclosed, but what we claim is:

1. In a multicolor weft replenishing mechanism having a plurality of reciprocable spaced bobbin releasing members, a color slide movable longitudinally and having two opposite angular movements, one movement occurring at indication of weft exhaustion only and on detecting picks and the other movement occurring every non-detecting pick of the loom, and a device to be engaged directly by the color slide independently of the members and moved from normal to abnormal position, said color slide simultaneously effecting movement of one of the members from normal to abnormal position on an indicating detecting beat of the loom, said color slide on a subsequent non-detecting beat of the loom engaging the device to return the same together with the previously moved member to normal position.

2. In a multicolor weft replenishing mechanism having a plurality of reciprocable spaced bobbin releasing members, a color slide movable longitudinally and having two opposite angular movements, one movement occurring at indication of weft exhaustion only and on detecting picks and the other movement occurring every non-detecting pick of the loom, a device to be engaged by the color slide at two spaced points and be raised by said color slide on indicating detecting beats, said color slide elevating one of the members

at the same time the device is raised, and said color slide on the next pick of the loom engaging the device to move the latter downwardly to normal position, and means to cause the previously raised member to be moved downwardly by the device when the latter is restored to normal position on a non-detecting beat independently of the longitudinal position of the color slide.

3. In a multicolor weft replenishing mechanism having a plurality of reciprocable spaced bobbin releasing members, a color slide movable longitudinally and having two opposite angular movements, one movement to raise the member occurring at indication of weft exhaustion only and on detecting picks and the other movement occurring every non-detecting pick of the loom, said members being parallel with each other, a device to be engaged by the color slide at two spaced points only one of which is on one side of a line central with respect to the members, said device to be lifted by the color slide upon exhaustion of weft, said color slide on the following non-detecting pick of the loom moving the device back to normal position to restore the previously raised member to normal position.

4. In a multicolor weft replenishing mechanism having a plurality of reciprocable spaced bobbin releasing members, a color slide movable longitudinally and having two opposite angular movements, one movement occurring at indication of weft exhaustion only, and on detecting picks and the other movement occurring every non-detecting pick of the loom, said color slide having two spaced fingers, and a device to be engaged by said fingers at two spaced points on indicating detecting beats of the loom to be raised simultaneously with the raising of one of the members, said color slide on a subsequent non-detecting beat of the loom causing engagement between the fingers thereof and the device at two spaced points to lower the device to cause lowering of the previously raised member, the vertical movements of said device being independent of the longitudinal position of the color slide.

5. In a multicolor weft replenishing mechanism having a plurality of reciprocable spaced bobbin releasing members, a color slide movable longitudinally and having two opposite angular movements, one movement occurring at indication of weft exhaustion only and on detecting picks and the other movement occurring every non-detecting pick of the loom, and a device to be moved from normal to abnormal position, said color slide simultaneously effecting movement of one of the members from normal to abnormal position on an indicating detecting beat of the loom, said color slide on a subsequent non-detecting beat of the loom operating the device to return the same together with the previously moved member to normal position, said

device being guided in its movements by two of said members.

6. In a multicolor weft replenishing mechanism having a plurality of reciprocable spaced bobbin releasing members, a color slide movable longitudinally and having two opposite angular movements, one movement occurring on a detecting pick and at indication of weft exhaustion only to raise the member and the other movement occurring every non-detecting pick of the loom in a direction effective to lower a raised member, and a device guided by two of said members to have movements in a direction substantially parallel to said members and capable of engaging all the members and the color slide and effective by engagement with the color slide when the latter has an angular movement on non-detecting beats of the loom to lower any previously raised member to normal position.

7. In an attachment for multicolor weft replenishing mechanisms having an angularly and longitudinally movable color slide and a plurality of vertically movable bobbin controlling slide members, the attachment being normally down but raised at exhaustion of weft by the color slide, the color slide effective to lower the attachment when the latter is raised, said attachment having a portion extending substantially parallel to the longitudinal movements of the color slide to be engaged by the latter in all longitudinal positions of the color slide, said attachment having further provision for engagement with any slide member which may be in raised position to lower the same when the attachment is lowered by the color slide.

8. In an attachment for multicolor weft replenishing mechanisms having an angularly and longitudinally movable color slide and a plurality of vertically movable bobbin controlling slide members, the attachment being normally down but raised at exhaustion of weft by the color slide, the color slide effective to lower the attachment when the latter is raised, said attachment having a portion extending substantially parallel to the longitudinal movements of the color slide to be engaged by the latter in all longitudinal positions of the color slide and having further provision for engagement with any slide member which may be in raised position to lower the same when the attachment is lowered by the color slide, said attachment having guide portions to engage two of the vertically movable members.

In testimony whereof we have hereunto affixed our signatures.

KENNETH J. UNWIN.
